UNITED STATES PATENT OFFICE.

ALBERT E. NEUMEYER, OF MORRIS, OKLAHOMA.

TUBING CLEANER.

Application filed February 9, 1927. Serial No. 166,874.

This invention relates to tube cleaners especially adapted for use in scraping paraffin from the tubings of wells.

By way of briefly explaining the purpose 5 of this invention it might be pointed out that in most pumping oil wells the accumulation of paraffin in the tubing tends to obstruct the free flow of oil and retard the movement of the sucker rods, especially the 10 down strokes thereof. The deposit of paraffin on the inner wall of the tubing decreases the cross sectional area of the tubing so that is not an easy matter to pull the rods or renew the cups and in many cases it is impossible 15 to return the rods to the well without first removing the tubing and blowing out each section thereof with steam to remove the paraffin, a labor consuming and costly task. The cost of thus removing the paraffin and 20 the loss of production incident to such removal has been the subject of much concern by those interested in the development of the industry. It is therefore a major purpose 25 of this invention to provide a tube cleaner or "paraffin pony" by which the paraffin may be scraped from the well tubing without removing the tubing and without excessive cost and loss of production.

More specifically the invention forming 30 the subject of this application is in the nature of a paraffin scraping member designed to be incorporated in the sucker rod so that by moving the sucker rod upwardly the paraffin scraping member may have scraping 35 contact with the paraffin to remove the same whereby sufficient tubing cross sectional area is restored to allow of the introduction of the sucker rod and at the same time to permit of the free flow of oil to the surface.

40 A further and equally important aim is to provide a "paraffin pony" of the character specified which will not require the abandonment of present equipment, will not depart from established pumping practices and 45 which may be incorporated in a sucker rod without the exercise of unusual skill.

Other objects and advantages will be apparent during the course of the following description.

50 In the accompanying drawing forming a part of this application and in which like numerals are employed to designate like parts throughout the same.

55 Figures 1 and 1^a illustrate the improved "paraffin pony" in place in a tubing.

Figure 2 is a perspective of the improved "paraffin pony" detached.

In the drawing the numeral 5 designates a well tubing of conventional or other design and installation and within which a sucker rod is reciprocated so that the pumping unit on the lower end thereof will lift the oil, all of which is old and well known to those skilled in the art.

The oil from some wells have a high paraffin content and during the pumping of the oil a portion of the paraffin becomes attached to the tubing. This cuts down the effective cross sectional area of the tubing for the flow of oil and interferes with the reciprocation of the sucker rod. To combat this, I employ a cleaning member unit embodying a stem 6 preferably, but not necessarily of the same diameter as the diameter of the sucker rod to which the same is designed to be connected. At this point attention might be directed to the fact that the ends of the stem 6 are provided with suitable boxes 7 and 8 by which the improved cleaning unit might be easily incorporated in the sucker rod at a 80 point below where paraffin is likely to occur.

Referring to Figure 2 it will be seen that two separate spiral blades 9 and 10 are formed on the stem 6 at spaced points so that as the device is moved upwardly it will come into scraping contact with the paraffin and will remove the same from the wall of the tubing. To counter-act any tendency of the stem to turn the two separate spiral scraping blades are coiled in opposite directions. Figure 2 clearly illustrates that the upper spiral cutting blade 9 is coiled downwardly in a clockwise direction, while the lower spiral body 10 is coiled downwardly in a counter clockwise direction. Thus the propensity of the stem 6 to turn and possibly cause a break in the sucker rods at one of the joints therein is overcome.

Also the lower spiral scraping blade is of a greater diameter than the lower scraping blade so it will cut somewhat deeper into the paraffin than the upper scraping blade. The greater diameter of the lower spiral scraping blade 10 results in uniform pressure engagement of the blades with the paraffin so this feature bears a definite relation to the reversed turning or coiling of the blades and there is therefore no appreciable turning of the stem 6 from this cause at least.

When it is desired to attack the paraffin

within the tubing the sucker rod is drawn upwardly to bring the upper and lower spiral cutting blades through the paraffin and to or near the surface so that the paraffin is scraped 5 from the wall of the tubing.

It is especially important to note that the scraping blades 9 and 10 are sufficiently long to center the device in the tubing so that the joints of the tubing cannot come into restraining relation to the improved cleaner. 10 In other words the spiral body cannot become hooked to any of the joints of the tubing. In fact it will be seen that the terminals of the spiral cutting blades adjacent the 15 ends of the stem are tapered and merge into the stem to avoid sharp corners and angles.

The employment of the improved "paraffin pony" does not necessitate the abandonment of present equipment or does it involve 20 any departure from established practice other than that disclosed in this specification.

No special skill is required to install the device and little time is consumed in simply 25 raising the sucker rods so that the blades 9 and 10 may have effective contact with the accumulated paraffin.

Having thus described the invention what is claimed is:

30 1. A tube cleaner for removing paraffin

from well tubings comprising a stem having means whereby the same may be incorporated in a pumping rod, and separate upper and lower spiral scraping blades formed on said stem and being coiled in opposite directions. 35

2. A tube cleaner for removing paraffin from well tubings comprising a stem having means whereby the same may be incorporated in a pumping rod, separate upper and lower spiral scraping blades formed on said 40 stem and being coiled in opposite direction, one of the spiral scraping blades being of a greater diameter than the other spiral scraping blade.

3. A device for scraping paraffin from well tubings comprising a stem having means whereby the same may be incorporated in a sucker rod below the point where paraffin is likely to occur, and upper and lower spaced spiral scraping blades on said stem and being of elongated formation whereby the same may center the stem in the tubing, the lower spiral cutting blade being greater in diameter than the upper spiral cutting blade whereby the two blades have substantially 50 uniform pressure engagement with the paraffin, said blades being coiled in opposite directions.

In testimony whereof I affix my signature.

ALBERT E. NEUMEYER.
